THREAD-EXTRACTOR FOR LOOMS.

Application filed June 17, 1922. Serial No. 569,108.

The present invention relates to an improvement in thread extractors for looms.

The object of the invention is to produce an improved thread extractor of simple construction, therefore inexpensive to build and of efficient and reliable form. To these ends the invention consists in the construction hereinafter described and particularly defined in the claims.

- 10 In the accompanying drawings illustrating the preferred form of the invention, Figure 1 is a front elevation of a portion of a loom provided with the improved thread extractor; Fig. 2 is a side elevation looking 15 toward the end of the loom, the lay being shown in section; Fig. 3 is a plan of the device; Fig. 4 is an axial section of the part of the mechanism, showing the extractor wheel and drum in section, the section being taken 20 in the plane of the axis of the extractor wheel and drum through the supporting bracket for the same; Fig. 5 is a sectional elevation of the bracket and support for the extractor wheel showing the extractor wheel 25 and the devices for operating it; and Fig. 6 is a vertical axial section of the extractor wheel, drum and supporting bracket.

The illustrated embodiment of the invention is described as follows: The thread extractor 30 consists, in general, of an extractor wheel mounted on a bracket secured to the end frame of the loom underneath the position occupied by the lay at its front center. The wheel is operated by connections with 35 the lay rock shaft to rotate intermittently during the operation of the loom, and as the bobbins are discharged from the shuttle, the thread extending from the bobbin to the lay is caught by the teeth of the extractor 40 wheel and pulled out of the loom.

The thread extractor consists of an extractor wheel 1, provided with extractor teeth 2. The wheel is supported on a stud 3 carried by the bracket 4, which bracket is securely 45 bolted to the end frame 5 of the loom. The stud 3 extends from the bracket 4 rearwardly, upwardly and toward the frame of the loom so that the axis of the extractor wheel occupies a position extending upwardly 50 from the bracket at a slight angle to the horizontal and toward the frame of the machine as shown best in Figs. 2 and 3. The wheel 1 is provided with a drum 6. The drum

carries a bearing block 7 at its rear end which is supported on the stud 3. At the 55 front end the drum and wheel carry the ratchet wheel 8 which is secured thereto and affords a bearing for the front end of the wheel and drum on the stud 3. The extractor wheel is rotated to the left, as viewed in Fig. 1, by means of a reciprocating extractor drive slide 10, the upper end of which carries a pawl 11 pivoted to it. The pawl is provided on one side with a pawl tooth and on the other with a weight, as seen in Fig. 5. When the slide 10 is depressed, the tooth of the pawl engages a tooth of the ratchet wheel 8 and rotates the latter, and thereby rotates the thread extractor and drum. The weight 60 normally holds the tooth of the pawl outwardly in position to engage the teeth of the ratchet wheel 8. A stop 13 on the rear side of the actuator slide 10 normally supports the pawl in the position shown in Fig. 5. During the rising movements of the actuator slide 10, the pawl swings clockwise, as viewed in Fig. 5, as it passes by the teeth of the ratchet wheel 8. The slide 10 is guided 65 on one side by the guard 15 projecting downwardly and rearwardly from the bracket 4, and on the other side by the guard 17 projecting rearwardly from the bracket 4, so that the slide is compelled to reciprocate within the limits permitted by these two guards. The bracket is further provided 70 with the ratchet guard 19 which extends rearwardly from the bracket and surrounds, covers and protects the ratchet wheel from 75 access of lint or thread.

The actuator slide 10 is reciprocated by 80 the lever 21 which is bolted on to the lay rock shaft 23 on the outside of the picker stick hub. A spring 25 normally pulls upon the slide 10 in the direction to hold it against the guard 15, from which it may be 85 pushed away slightly during its rising movement. By reference to Figures 1 and 2, it will be seen that when the bobbin is changed and the ejected bobbin is discharged from the shuttle, the thread 27 extending from it 90 to the lay occupies a position in front of the extractor wheel, as shown in Fig. 2, then as the lay retreats after replenishment, the thread occupies a position indicated at 29, Fig. 2, thus being drawn across the teeth of 95 the extractor wheel. The position of the 100

thread as shown at 29 in Fig. 2 is such that it appears in Fig. 1 as shown at 31. During this retracting movement of the lay, the rotation of the extractor wheel engages the 5 thread extending to the exhausted bobbin and pulls it out of the lay. The bracket 4, upon which the extractor wheel and drum are mounted, is provided with an upwardly extended thread guarding disk 33 over the 10 edge of which the thread extends when the extractor wheel is operating to pull it out of the lay. As the extractor wheel rotates, it carries the thread along on the edge of this guarding disk 33 until the thread strikes 15 the guard 35 over which it draws the thread and which operates to guide the thread from the extractor on to the drum on which the thread, if long enough, is wound up and thereby removed from opportunity of accumulation 20 in places where it will interfere with the operation of the loom. This bracket 4 is also provided with bobbin can positioning lugs 37 and 39, which receive the bobbin can between them in the position 25 indicated at 41 in Figs. 1 and 2, by dash and dot lines.

Upon the change of filling being indicated by the filling feeler, the change is effected when the shuttle is in the shuttle box over 30 the bobbin can and thread extractor. The bobbin ejected from the shuttle falls into the can and the thread extending from the bobbin to the lay, on the first backward beat of the lay, is engaged by the teeth of the extractor wheel, and that portion of the thread 35 extending from the extractor wheel to the lay is wound up on the drum of the extractor, as well as that portion of the thread extending from the extractor to the bobbin 40 in case it is not, as is ordinarily the case, broken near the extractor wheel. If a portion of this thread enters the space between the extractor wheel and the bracket 4, it will be prevented from becoming entangled 45 with the slide for operating the extractor wheel by the guards 17 and 19, the former of which prevents thread from approaching the slide on one side and the latter of which prevents approach of the thread on the other 50 side.

Having thus described the invention, what is claimed is:

1. A thread extracting device for looms having, in combination, a thread extracting wheel provided with thread engaging devices, mounted with its axis extending from the front toward the rear of the machine and supported in position to engage a thread from an ejected bobbin upon the backward movement of the lay, and means for actuating 60 the extractor wheel.

2. A thread extracting device for looms having, in combination, a rotary thread extracting device mounted with its axis extending from the front toward the rear of 65 the loom, and means for rotating it to engage the thread extending from the lay to an ejected bobbin to pull the thread out of the lay upon the backward beat thereof.

3. A thread extracting device for looms 70 having, in combination, a thread extracting wheel mounted to rotate on an axis extending from front to rear of the loom and located below the shuttle box on the weft replenishing side of the loom, and means for 75 rotating the extractor.

4. A thread extracting device for looms having, in combination, an extractor wheel provided with thread engaging teeth mounted with its axis inclined and extending 80 rearwardly and upwardly and supported in position to engage a thread from an ejected bobbin upon rearward movement of the lay, and means for rotating the extractor wheel.

5. A thread extracting device for looms having, in combination, a thread extracting wheel provided with thread engaging teeth, a drum secured to the thread extracting wheel, a shaft on which the wheel and drum are mounted extending from the front toward the rear of the machine and adapted to be supported beneath the shuttle box on the weft replenishing side of the loom, a ratchet wheel on the shaft, a guard for preventing access of lint to the ratchet, and a reciprocating lever having provision for engaging the ratchet to rotate the wheel and drum intermittently.

JONAS NORTHROP.
